(**) Term: **14 Years**

CLAIM

(21) Appl. No.: **29/213,412**

The ornamental design for a end cap for fluorescent lamp, as
shown.

(22) Filed: **Sep. 16, 2004**

DESCRIPTION

(30) Foreign Application Priority Data

FIG. 1 is a perspective view showing my design;

Mar. 18, 2004 (EP) 000147517-0001

FIG. 2 is a front elevational view thereof;

(51) LOC (6) Cl. **26-04**

FIG. 3 is a rear elevational view thereof;

(52) U.S. Cl. **D26/3**

FIG. 4 is a right side elevational view thereof;

(58) Field of Search D26/1-4; 313/313,

313/315, 318, 320, 493; 315/52, 53, 56,

57, 58

FIG. 5 is a left side elevational view thereof;

(56) References Cited

FIG. 6 is a top plan view thereof; and,

U.S. PATENT DOCUMENTS

FIG. 7 is a bottom plan view thereof.
